Ward, Kirby & Smith

UNITED STATES PATENT OFFICE.

WILLIAM J. BAXTER, OF NEW YORK, N. Y.

PRINTED COTTON FABRIC.

Application filed October 15, 1924. Serial No. 743,741.

To all whom it may concern:

Be it known that I, WILLIAM J. BAXTER, a citizen of the United States, and resident of the city of New York, in the county and State of New York, have invented certain new and useful Improvements in Printed Cotton Fabrics, of which the following is a specification.

The invention relates to printed cotton fabrics, and more particularly to cotton fabrics so printed, and preferably so finished and printed as to give the cotton fabric the appearance of French flannel of the character used for shirtings in which there are threads of contrasting color, preferably a delicate or soft contrast, woven in the fabric.

There are different types or characters of such French flannel; for example, one kind has threads of contrasting color appearing at somewhat irregular intervals over the surface of the fabric, to give the appearance of rather indeterminate fine spots and streaks or streaky zones.

In my copending application Serial No. 703,711, filed April 2, 1924, for printed cotton fabrics, I have described a cotton fabric printed to resemble this character of French flannel as more fully described in said specification.

Briefly stated, in simulating that character of French flannel, I printed over the surface of the cotton fabric fine dots preferably irregularly grouped and of somewhat irregular character, to produce a soft toned stippled effect or ground tone, with streaks or streaky zones of a somewhat darker shade extending irregularly over the ground tone, the streaks extending irregularly over the ground in the same general direction, and of varying widths and soft and somewhat blurred in appearance.

Another type or character of such French flannel is one in which the colored threads extend in rather fine closely spaced diagonal lines across the length of the fabric, for example, fine blue diagonal lines alternating with fine uncolored diagonal lines. Due to the difference in texture between cotton and flannel, it is impossible to simulate this appearance by simply printing the fine solid or substantially solid colored lines diagonally across the fabric, and one of the objects of the present invention is to provide a

printed cotton fabric to simulate this character of French flannel. Broadly stated, this is accomplished by printing on the fabric the above-mentioned stippled ground tone, except for fine closely spaced parallel lines of the surface running diagonally over the fabric, which lines are substantially free or sufficiently free of said color to produce a contrast between the stippled ground and the said lines to give a serge-like effect. To further simulate a serge-like flannel effect, I utilize grey cotton fabric, i. e., unbleached or only partly bleached fabric, and in addition the fabric is given a soft finish, preferably produced by roughening the surface of the flannel after the printing.

The invention consists in the novel printed cotton fabric herein described in connection with the drawings forming a part of this specification and illustrating by way of example certain preferred embodiments of the invention. The invention will be more particularly pointed out in the appended claims.

Further objects and advantages of the invention will more fully appear from the following description taken in connection with the accompanying drawings illustrating by way of example fabric embodying the invention, in which—

Fig. 1 shows the right side or upper surface of a fabric embodying the invention;

Fig. 2 may be taken to illustrate the upper surface of a fabric of somewhat different pattern also embodying the invention, or it may illustrate the reverse or under surface of the fabric the upper surface of which is illustrated in either Fig. 1 or Fig. 3; and

Fig. 3 illustrates a fabric like Fig. 1, but having an overprint, and also embodying the invention.

Fig. 2 illustrates the above-mentioned serge effect flannel-like fabric produced by printing the stippled ground tone with fine parallel diagonal lines across the same. In this figure some of the larger dots for producing the stippled ground tone effect are illustrated by numerals 1; while the parallel diagonal uncolored or sparsely colored lines are illustrated by numerals 2. It will be observed that the dots are of varying size, character and groupings so as to give the above referred to soft stippled ground tone effect to the greatest advantage. It will also be observed that the parallel diagonal lines

2 are substantially free or sufficiently free of said color to produce a contrast giving the 70
serge-like effect.

Fig. 1 illustrates a fabric having the same 75
stippled effect produced by the dots 1 with 80
the same serge effect produced by the diagonal lines 2, and in addition this fabric has 85
printed thereon the above referred to soft 90
streaky effect illustrated by the streaks or 95
streaky zones 3, which are preferably of the 100
same color as the stippled ground but of 105
darker shade, due to closer massing of the 110
colored spots or color, although these streaky 115
zones may be produced by an entirely different 120
color which will softly contrast or blend 125
with the stippled ground.

Fig. 3 illustrates a fabric having the stippled ground serge effect and streaks or zones 130
thereover, as shown in Fig. 1, and in addition 135
having what I term a linear overprint 140
illustrated by the clearly defined bold lines 145
4. It will be observed that each of these 150
three figures embodies the stippled ground 155
with serge effect.

25 The use of the somewhat irregular indeterminate soft stippled coloring in between 160
the fine uncolored diagonal lines, and particularly 165
with the use of grey fabric with soft 170
finish, provides a fabric strikingly like said 175
diagonal patterned French flannel, and to 180
the casual observer looks exactly like a serge 185
French flannel, the softness of the stippled 190
coloring, together with the greyish color and 195
soft finish, greatly reducing the harsh effect 200
or effect.

30 that would be produced by simply printing 205
colored diagonal lines on the cotton fabric. 210
In fact, even upon a close examination by 215
one not thoroughly familiar with fabrics, the 220
said printed cotton fabric has every appearance 225
of the said French serge-finish flannel. 230
Because of the relative cheapness of cotton 235
as compared with wool, as well as because of 240
the relative coolness of the cotton as compared 245
to wool for summer use, the said 250
printed cotton fabric is highly desirable. It 255
gives the "outing" effect of a French flannel 260
shirt without the cost and the undesirable 265
warmth of the wool in summer.

35 The above-mentioned serge effect may be 270
used simply with the stippled ground tone 275
above described, or it may be used in conjunction 280
with the streaky effect also described in my 285
said copending application. In the said copending 290
application I claim the cotton fabric with the streaky 295
effect on the stippled ground tone, regardless of 300
whether the fabric may be so printed as to 305
also give the serge effect herein described and 310
claimed.

40 Another feature of the present invention 315
is to provide a printed cotton fabric resembling 320
French flannel of the character used 325
for shirtings, on which cotton fabric one surface 330
is printed to resemble French flannel of 335
any character above mentioned, while the 340
other surface is printed over to give said 345
stippled ground tone effect with or without 350
an additional characteristic of the French 355
flannel, so that said second mentioned or 360
back surface of the cotton fabric is suffi- 365
ciently similar in appearance to the first 370
mentioned or front surface to represent the 375
back of said woven flannel fabric, the front 380
surface of which is represented by the front 385
of the printed cotton fabric; the back sur- 390
face of the cotton fabric being sufficiently 395
distinguished from its front surface to en- 400
able the cutter to distinguish the back from 405
the front in making up garments from said 410
cotton fabric. As a rule, the two surfaces of 415
the woven flannel fabric are somewhat dif- 420
ferent in appearance so that a cutter can tell 425
one from the other and thus avoid any errors 430
in cutting garments, such for example as 435
having the back of the fabric exposed for 440
the collar or cuffs while the front of the fab- 445
ric is exposed for the rest of the garment. I 450
have found that where both sides of the cot- 455
ton fabric are printed the same, the cutters 460
have frequently exposed the wrong side of 465
the fabric in making up parts of garments, 470
and even although the printing may be the 475
same on both surfaces the finish is or may 480
not be the same, and the mistake can be de- 485
tected by close observations, hence the im- 490
portance of printing both sides of the cotton 495
fabric with a flannel-like effect having one 500
distinguishable from the other in character 505
or effect.

55 For example, as shown in Fig. 1, I may 500
print on the "right" or upper surface the 505
stippled ground effect so applied as to im- 510
itate the serge flannel with the streaky effect 515
over the same, and I may omit the streaky 520
effect from the reverse or under surface, as 525
shown in Fig. 2, or I may apply the stippled 530
ground tone and streaky effect without serge 535
effect on one surface, and the stippled 540
ground serge effect on the other surface, or I 545
may apply an overprint striped or checkered 550
line effect over the serge effect ground for one 555
surface, and eliminate said striped or check- 560
ered overprint from the reverse surface. A 565
very satisfactory flannel effect may be pro- 570
duced, for example, by printing the stippled 575
ground tone with serge effect and streaks on 580
the upper surface with an overprint of bold 585
lines across the streaks, as shown in Fig. 3, 590
and then on the back of the fabric print the 595
stippled ground tone with serge effect, and 600
with the bold line overprint, but eliminate 605
the streaks. These various combinations are 610
only by way of illustration and are not to 615
be considered as limiting the scope of the 620
invention.

65 The dots used for the stippled effect are 625
preferably of varying character or outline 630
and irregularly grouped or massed to give 635
a soft blending tone to the fabric, although 640
the dots are so small individually that their 645

outline or shape is not observable upon casual observation. As mentioned in my said prior application, the streaks on the fabric when used are preferably of the same 5 color as the stippled ground, but have a darker shade due to a closer massing of the color along the streaks or streaky zones, and also preferably the dots or colored stippling is of one color, some of the stippling dots 10 being preferably more prominent than others to enhance the flannel-like effect.

By various combinations of the features above described a large number of patterns may be provided resembling said French 15 flannel.

While I have described my invention with particularity in connection with the fabric patterns shown in the drawings, it will be understood by those skilled in the art, after 20 understanding my invention, that modifications may be made therein without departing from the spirit or scope of the invention, and in the appended claims I wish to cover all such modifications as come within the 25 spirit of the invention.

Having thus described my invention, what I claim as new and desire to secure by Letters Patent, is:

1. As an article of manufacture, a cotton 30 fabric printed to resemble in appearance French flannel of the character used for shirtings having threads of contrasting color woven therein, the cotton fabric having an even surface printed over with closely spaced 35 fine colored dots to give a stippled ground or tone except for fine closely spaced parallel lines of said even surface running diagonally over the fabric which lines are substantially or sufficiently free of said color to 40 produce a contrast between the stippled ground and said lines to give a serge-like flannel effect.

2. As an article of manufacture, a cotton 45 fabric printed to resemble in appearance French flannel of the type used for shirtings having threads of contrasting color woven therein, the cotton fabric having a soft finish even surface printed over with closely spaced fine dots of the same color irregularly massed 50 to give a stippled ground effect except for fine closely spaced parallel lines of said surface running diagonally over the fabric, which lines are substantially or sufficiently free of said color to produce a contrast be- 55 tween the stippled ground and said lines to give a serge-like flannel effect.

3. As an article of manufacture, a cotton 60 fabric printed to resemble in appearance french flannel of the type used for shirtings having threads of contrasting color woven therein, the cotton fabric being grey fabric with a soft finish, printed over with closely spaced fine colored dots irregularly grouped to give a soft toned stippled ground effect 65 with fine closely spaced parallel lines of its

surface running diagonally over the fabric, which lines are substantially or sufficiently free of color to produce a contrast between the stippled ground and said lines to give a 70 serge-like flannel effect.

4. As an article of manufacture, a cotton 75 fabric printed to resemble in appearance French flannel of the type used for shirtings, having threads of contrasting color woven therein, the cotton fabric being grey fabric with a soft finish, printed over with closely spaced fine colored dots irregularly grouped to give a soft toned stippled ground effect, and with streaks of a somewhat darker shade extending thereover, said 80 streaks extending irregularly in the same general direction and being of varying widths and soft and somewhat blurred in appearance, said fabric also having fine closely spaced parallel lines of its surface 85 running over the fabric diagonally of said streaks and substantially or sufficiently free of color to produce a contrast between the stippled ground and said lines to give a 90 serge-like flannel effect.

5. As an article of manufacture, a cotton 95 fabric printed to resemble in appearance French flannel of the type used for shirtings, having threads of contrasting color woven therein, the cotton fabric having a soft finish even surface printed over with closely spaced fine dots of the same color irregularly massed to give a stippled ground effect, and having an overprint effect of clearly defined lines of a different color from 100 the stippled ground, and having fine closely spaced parallel lines of the surface running over the fabric diagonally of said overprint lines and substantially or sufficiently free of color to produce a contrast between the 105 stippled ground and said diagonal lines to give a serge-like flannel effect.

6. As an article of manufacture, a cotton 110 fabric printed to resemble in appearance French flannel of the type used for shirtings having threads of contrasting color woven therein, the cotton fabric being grey fabric with a soft finish printed over with closely spaced fine colored dots irregularly grouped to give a soft toned stippled ground effect, and with streaks of a somewhat darker shade extending thereover, said streaks extending irregularly in the same general direction and being of varying widths and soft and somewhat blurred in appearance, said fabric also having fine closely spaced parallel lines of its surface 115 running over the fabric diagonally of said streaks and substantially or sufficiently free of color to produce a contrast between the stippled ground and said diagonal lines to give a 120 serge-like flannel effect, and having an overprint effect of clearly defined lines extending transversely of said diagonal lines.

7. As an article of manufacture, a cotton fabric printed to resemble in appearance French flannel of the character used for shirtings having threads of contrasting color woven therein, the cotton fabric having one of its surfaces printed over with fine dots so as to give a stipple-like soft ground tone or effect and with streaks of a somewhat darker shade extending thereover, said 5 streaks extending irregularly in the same general direction and being of varying widths and soft and somewhat blurred in appearance, the other surface of said fabric being also printed over with fine dots so as 10 to give said stipple-like soft ground tone effect and being sufficiently similar in appearance to the first mentioned surface to represent the back of said woven flannel fabric the front surface of which is represented 15 by the first mentioned printed effect, but sufficiently distinguishing from said first mentioned printed surface to enable the cutter to distinguish one from the other in making up garments from said fabric.
8. As an article of manufacture, a cotton fabric printed to resemble in appearance French flannel of the character used for shirtings having threads of contrasting color woven therein, the cotton fabric being grey 20 fabric with a soft finish, having one surface printed over with closely spaced fine colored dots to give a soft toned stippled ground ef-

fect, and with streaks of a somewhat darker shade extending thereover, said streaks extending irregularly in the same general direction and being of varying widths and soft and somewhat blurred in appearance, 35 said fabric surface also having fine closely spaced parallel lines of its surface running over the fabric diagonally of said streaks and substantially or sufficiently free of color to produce a contrast between the stippled ground and said lines to give a serge-like flannel effect, the other surface of said cotton fabric being likewise printed over to 40 give said stippled ground effect and also having fine closely spaced parallel lines of its surface running over the fabric diagonally of the same and substantially or sufficiently 45 free of color to produce a contrast between the stippled ground and said lines to give a serge-like effect, said last surface of the fabric being sufficiently like the first printed surface to represent the back of said woven fabric the front surface of which is represented by the first mentioned printed effect, but sufficiently distinguishing from said 50 first mentioned printed surface to enable the cutter to distinguish one from the other in making up garments from said fabric.

In testimony whereof I have signed my name to this specification.

WILLIAM J. BAXTER
